UNITED STATES PATENT OFFICE

FRANK A. DORSCH, MILWAUKEE, WISCONSIN

GAME

Application filed February 20, 1930. Serial No. 429,971.

This invention relates to improvements in games.

It is one of the objects of this invention to provide an improved game which is adapted for the entertainment of both young and old, and which may be played in a number of different manners by two or more persons.

A more specific object of this invention is to provide a game utilizing a belt bearing a plurality of characters, the said belt being movable within a casing having a plurality of normally closed windows, and said characters on the belt being adapted to register with said windows so that if a predetermined character is stopped at a selected window the person who has selected said window will gain an advantage in the game.

A further object of this invention is to provide a game which is simple in construction, inexpensive to manufacture, and well adapted for the purpose described.

With the above and other objects in view, the invention consists of the improved game, and all its parts and combinations, as set forth in the claims, and all equivalents thereof.

In the accompanying drawing, illustrating one complete embodiment of the preferred form of the invention, in which the same reference numerals designate the same parts in all of the views:

Fig. 1 is a front elevation of the improved game;

Fig. 2 is a horizontal sectional view taken on line 2—2 of Fig. 1;

Fig. 3 is a vertical sectional view taken on line 3—3 of Fig. 2; and

Fig. 4 is a sectional view taken on line 4—4 of Fig. 1.

Referring to the drawing, the numeral 8 designates an elongated box-like casing, closed on all sides, and mounted on a base member 9. The base member is preferably provided with ball casters 10.

Journalized in the top and bottom portions 45 of the casing at one end thereof is a shaft 11, and at the other end of the casing, an L-shaped rod 12 is positioned between the side and the bottom portions. The rod 12 carries a rotatably mounted roller 13, and the shaft 50 11 is provided with spaced apart collars 14.

A crank 15 is fitted in the upper end of the shaft 11 to permit manual rotation of the latter.

An endless belt 16 extends around the shaft 11 between the collars 14, and around the roller 13 on the rod 12. The belt has delineated thereon a plurality of characters 17 which are spaced apart, and which extend the length of the belt. In the preferred form illustrated, these characters are the numbers 60 one to twelve enclosed alternately by circles and squares.

The side of the casing adjacent to the belt is formed with a plurality of spaced apart openings 18 with which the characters on the belt are adapted to register and through which said characters may be seen and read. Extending above each opening is a pin 19 on which a shutter 20 is pivotally mounted. The shutters have identifying characters delineated thereon, preferably on both sides, and in the preferred form of the invention, these characters are the letters of the alphabet. Pins 21 extend outwardly from the casing below the windows, and each pin has a removable tag 22 suspended therefrom. Each tag is marked with an identifying character identical to that borne by the shutter above.

Rotatably positioned in the top of the casing are poles 23 of flags 24, there being one 80 flag for each of the side openings 18. The flags are marked in order with characters corresponding to the characters on the belt 16, the said characters being borne by only one side of each flag.

In use each player selects a number of tags 22, and removes them from the pins 21. If two persons are playing, each selects six tags; if three are playing, four tags, and so on. The crank on top of the casing is then 90 turned a few times to move the belt and the numbers thereon, all of said numbers being concealed by the shutters 20. Next, the score-keeper, or one of the players, lifts one shutter, revealing a number, such as the number 6 95 shown in Fig. 1. The indicator flag on top of the casing, which corresponds to the number revealed, is then turned to face the players, as is also shown in Fig. 1. The flag indicates what the winning number will be, and 100

thus confusion and argument is eliminated. The shutter is now closed, and the crank is given a few more turns. Then all of the shutters are raised, and the player who holds the 5 identification tag for the opening at which the winning number is positioned is the victor.

A modification of the above game may be played as follows: The winning number is determined and the tags 22 are selected in 10 the manner before explained. In a receptacle representing the bank a quantity of peas or beans is placed. The holder of the identification tag for the opening where the winning number is stopped collects a forfeit in peas 15 or beans from all holding tags which identify numbers of less value than the winning number, the forfeit being equal to the difference in value between each loser's number and the winning number. At the end of a definite 20 number of plays, such as twelve, the person with the greatest number of forfeits wins.

Still another type of game may be played as follows: Identification tags are selected as in the first mentioned game, but the indicator 25 flags 24 are not used. Each player takes a piece of paper and draws either a square or circle thereon, and beneath it writes the numbers one to twelve. The player who chooses a circle can use only those numbers which 30 appear in the opening identified by his tag, which are enclosed with a circle, and if a square appears in the opening, it does not count, and vice versa. If a person who has chosen a circle has a number enclosed with a 35 circle stop opposite to one of his openings, he draws a circle around the corresponding number on his piece of paper. The first player to enclose all of the number on his sheet of paper wins.

40 Although only one form of the invention has been shown and described, it is not desired to be limited to the exact showing, as the broad concept of the invention includes all changes and modifications as may come within the scope of the claims.

45 What I claim is:

1. A game comprising a wall having a plurality of openings therein, a movable shutter for each opening, each shutter having an 50 identifying character thereon, a removable identifying tag for each opening, having a character thereon like that on the shutter for said opening, and means movable behind said wall having a plurality of different characters thereon which are adapted to be exposed when said shutters are opened.

2. A game comprising a wall having a plurality of openings therein, a movable shutter for each opening, each shutter having an 60 identifying character thereon, a removable identifying tag for each opening having a character thereon like that on the shutter for said opening, means movable behind said wall having a plurality of different characters 65 thereon which are adapted to be exposed

when said shutters are opened, and a plurality of identifying members each bearing a character like one of the characters on said movable means.

3. A game comprising a wall having a 70 plurality of openings therein, a movable shutter for each opening, each shutter having an identifying character thereon, a removable identifying tag for each opening having a character thereon like that on the shutter for said opening, and means movable behind said wall having a plurality of different numerals thereon which are adapted to be exposed when said shutters are opened.

4. A game comprising a wall having a 80 plurality of openings therein, a movable shutter for each opening, each shutter having an identifying character thereon, a removable identifying tag for each opening having a character thereon like that on the shutter for said opening, means movable behind said wall having a plurality of different numerals thereon which are adapted to be exposed when said shutters are opened, and a plurality of identifying members, each bearing a 85 numeral like one of the numerals on said movable means.

5. A game comprising a wall having a plurality of openings therein, a movable closure for each opening, an identifying character 95 adjacent each opening, a removable identifying tag for each opening having a character thereon like the character adjacent said opening, and means movable behind said wall having a plurality of different characters 100 thereon which are adapted to be exposed when said closures are opened.

In testimony whereof I affix my signature.
